UNITED STATES PATENT OFFICE.

FLOYD W. WOOLEVER AND GEORGE M. STAINS, OF AKRON, OHIO.

RAILROAD-TIE.

1,297,976.

Specification of Letters Patent.

Patented Mar. 18, 1919.

Application filed April 24, 1918. Serial No. 230,458.

To all whom it may concern:

Be it known that we, FLOYD W. WOOLEVER and GEORGE M. STAINS, citizens of the United States, residing at Akron, in the county of Summit and State of Ohio, have invented certain new and useful Improvements in Railroad-Ties; and we do hereby declare the following to be a full, clear, and exact description of the invention, such as 10 will enable others skilled in the art to which it appertains to make and use the same.

This invention relates to railroad ties and the primary object of the invention is to provide an improved metallic railroad tie, 15 which is so constructed as to eliminate the use of the ordinary wooden ties and at the same time retain the resilient qualities of the same.

Another object of the invention is the provision of an improved metallic tie formed of an elongated rolled metallic plate having upstanding spaced longitudinally extending ribs, the ends of the plate being bent upwardly and then inwardly toward each other 25 to provide housings for receiving the resilient wooden blocks, the ribs forming guides for receiving the blocks to prevent lateral movement thereof.

A further object of the invention is to 30 provide an improved metallic tie which can be used as a tie for supporting switches and can also be used for supporting water troughs used where engines take on water while moving.

A still further object of the invention is to provide an improved metallic tie of the above character, which is durable and efficient in use, one that is simple, and easy to manufacture, and one that can be placed 35 upon the market at a reasonable cost.

With these and other objects in view, the invention consists in the novel construction, arrangement and formation of parts, as will be hereinafter more specifically described, 40 claimed and illustrated in the accompanying drawings, forming a part thereof, in which:—

Figure 1 is a plan view of the improved metallic tie, showing the plate used in connection with the ties for supporting the switches, said plate being broken away to illustrate the support therefor,

Fig. 2 is a side elevation of the improved tie partly in section showing the plate used 55 in connection with the tie when the same is to be used for supporting the switches,

Fig. 3 is a detail transverse section taken on the line 3—3 of Fig. 2,

Fig. 4 is a detail transverse section taken on the line 4—4 of Fig. 2,

Fig. 5 is a fragmentary longitudinal section taken through the tie showing the same constructed in accordance with our invention when the same is to be used in the ordinary manner, and

Fig. 6 is a detail perspective view of one end of the tie.

Referring to the drawings in detail wherein similar reference numerals designate corresponding parts throughout the several views, the numeral 1 generally indicates the improved metallic railroad tie, which is formed of an elongated rolled metallic plate having the spaced longitudinally extending upstanding ribs 2, which form a channel between the same, the purpose of which will hereinafter more fully appear. The end of the plate is bent upwardly at right angles to form end walls 3 and the same are then bent inwardly toward each other at right angles as at 4, which overlie and are parallel with the bottom of the plate. The top wall 4 and the end walls form a suitable housing for receiving the wooden or other resilient block 5, which is positioned between the ribs 2, which prevent lateral movement thereof. The wooden blocks are first placed in the center of the tie and, are then pushed inwardly toward the end thereof until the same reach the side walls 3. The tie is formed with a plurality of apertures 4a therein at the time of rolling of the tie adjacent each end thereof to permit water to readily drain from the blocks 5. The blocks may be suitably treated with creosote or the like so as to prevent deterioration thereof. The upper surface of the walls 4 are formed smooth and receive the ordinary railroad rails 6, which are held in position by clips 7, which are bolted or otherwise secured to the tie.

Suitable supports are provided for the free ends of the upper walls 4 to prevent an undue sagging and bending of the same and as shown in Figs. 1 and 2 the same consists of I-beams 8, which are bolted as at 9 to the upper and lower walls. When the improved tie is to be used for supporting switch points and the like, a suitable plate 10 is provided having the downwardly extending ribs 11, which are positioned in engagement with the sides of the I-beams

8 which prevent lateral movement, and the end of the plate is suitably bolted to the I-beams as at 4. When the tie is to be used on straight roadways, supports for 5 the upper walls 4 are formed from channel iron 12 and the flanges thereof are bolted as at 13 to the upper and lower walls of the tie.

This form of tie is also especially applicable for supporting water troughs used 10 in connection with railroad systems, in which the engines thereof take on water while moving as the tanks can be erected on the ribs 2 and suitably bolted to the tie. 15 From the foregoing description, it can be seen that an improved metallic tie is provided, which will form a resilient support for rails and which is of durable and efficient construction and which will last 20 for an indefinite period of time.

In practice, we have found that the form of our invention illustrated in the accompanying drawings and referred to in the above description, as the preferred embodiment, is the most efficient and practical; 25 yet realizing the conditions concurrent with the adoption of our device will necessarily vary, we desire to emphasize the fact that various minor changes in details of construction, proportion and arrangement of parts may be resorted to, when required 30 without sacrificing any of the advantages of our invention as set forth.

What we claim as new is:—

35 1. A metallic railroad tie constructed of a single blank of rolled metal having the

ends thereof bent upwardly to provide end walls and then inwardly toward each other to provide top walls, longitudinally extending reinforcing ribs formed on the inner 40 surface of the plate, resilient blocks fitted in between the upper and lower walls of the plate, as and for the purpose specified.

2. A metallic railroad tie comprising an elongated plate having the ends thereof bent 45 upwardly to provide end walls, and then inwardly toward each other to provide top walls, resilient blocks fitted between the upper and lower walls, supports interposed between the ends of the top walls and the 50 lower walls, and ribs formed on the plate and engaging the sides of the resilient blocks to prevent relative lateral movement thereof.

3. A metallic railroad tie comprising an elongated plate having spaced longitudinally extending upstanding ribs formed thereon, the ends of the plate being bent 55 upwardly at right angles and then inwardly toward each other, blocks fitted under the bent ends, supports for the free ends of the bent ends of the plate and a detachable plate interposed between the free ends of the plate and engaging said supports, as and for the purpose specified.

In testimony whereof we affix our signatures in presence of two witnesses.

FLOYD W. WOOLEVER.
GEORGE M. STAINS.
